UNITED STATES PATENT OFFICE.

WILLIAM L. KUBACH, OF NORWALK, OHIO.

AUTOMATIC RAILWAY-SWITCH.

937,819.

Specification of Letters Patent. Patented Oct. 26, 1909.

Application filed March 9, 1908. Serial No. 419,829.

To all whom it may concern:

Be it known that I, WILLIAM L. KUBACH, a citizen of the United States, and resident of Norwalk, county of Huron, State of Ohio, have invented certain new and useful Improvements in Automatic Railway-Switches, of which I declare the following to be a full, clear, and exact description, such as will enable others skilled in the art 10 to which it appertains to make and use the same.

The objects of the invention are to provide a form of railway switch which can be thrown to open or closed position by means 15 of an operating device on the engine cab or some other portion of the train, and in this manner be under the control of the train employees, and operated by them or by any designated one of them at any predetermined 20 mine distance from the switch point, and in this manner obviate all danger to life and limb, now prevalent from open and neglected switches. The device is also adapted to be operated from either direction and 25 from tracks diverging from the switch, and is so arranged that the speed of the train or car will make no difference in the result.

Further objects are to provide a positive form of mechanism that can not fail to work 30 unless maliciously tampered with and which assumes a perfectly rigid position such that only a breakage of the parts or the normal action of the switch can alter the position of the parts.

Further the device is attachable to all forms of switches and will in no way interfere with hand operation if so desired.

Again the application of power required to operate the switch can be regulated so as 40 to prevent it from being operated by children or tramps; and a special operating lever may be provided for the use of trainmen to overcome the necessary provided resistance.

A further advantage is provided in an automatic spring action of the parts during 45 a portion of their throw whereby the employment of accessory springs of all sorts is avoided. The absence of springs tends 50 therefore to insure a positive action of the switch.

To obtain these advantages I employ the folding or hinged bars arranged to alternately operate as draw bars and pressure 55 rods and placed intermediate between the switch points and ribs, and the operating

means therefor located both upon the track, and upon the truck or platform of the train member above, and the various details of construction and combination and arrangement of the various parts as hereinafter described, shown in the accompanying drawings and specifically pointed out in the claims.

In the accompanying drawings, Figure 1 is a plan view of a railway switch showing the operating rods therefor in position; Fig. 2 is a longitudinal section thereof on the center line; Fig. 3 is a plan view of a parallel track in continuation of Fig. 1 showing an operating shaft and levers for the switch operating bars, arranged for action when a train or any one member thereof is approaching from the rear of the switch and designed to prevent running into an open switch from the rear.

In these drawings 1, 1 represent the rails of the straight track, 2, 2, the rails of the parallel or divergent track, and 3 the inner switch tongue, and 4 the outer tongue or rail point.

The operating devices comprise the bars 5 and 6 which are centrally jointed by means of oppositely opening hinges or knuckles 7 and 8 and are provided preferably with shoulders 9 and 10 which serve to prevent backward movement of the parts beyond a predetermined degree and insure a rigid position when the two members of each bar assume a rectilinear position. It will be seen that the bar 5 opens only to the left and the bar 6 only to the right in the position shown in Fig. 1 and that the bar 5 connects the outer rail with the switch tongue 3 while the bar 6 connects the inner rail with the outer tongue 4.

A main operating rod 12 extends along the track to any predetermined distance from which the requirements of safety and convenience might dictate the operation of the switch. This rod 12 is reciprocated to operate the switch by means of the rock shaft 13 and arm 14 to which the end of the rod is attached.

Rock arms 15 and 16 placed at an angle 105 to each other project in turn above the rock arm and are engaged by means of a suitable tripping device 17 underneath the cab or car of the train as it passes, and by intermediate striking mechanism. The end 110 of the rod 12 nearest the switch is pivotally connected with each operating bar by means

of links 18 and 19 at the respective hinge pivots, so that the bars will be alternately opened and closed as the rod 12 moves in one direction or the other. The rock arms 15 and 16 are not arranged in the same plane but at a slight distance from each other so that either can be operated independently from the car above, by means of a separate tripping device under the control of the operator one tripping device serving to operate one rock arm to close the switch and the other tripping device serving to operate the other arm to open the switch. The tripping device is shown to be capable of elevation so as to avoid one or both of the rock arm operating devices if necessary, and is preferably provided with a shoe hinged at 20 which will tilt when it strikes a rock arm moving device when the train is going in the reverse direction. Provision is made for moving the rock arms without giving them a blow severe enough to break them and this is accomplished by means of the inclined striking bars 21 pivoted at 22 and connected with the rock arms by means of links 23 in substantially a vertical position and hence give a more gradual movement thereto than if they were directly engaged by the shoes.

In the use of the device it will be seen that when one hinged bar is compressed at the joint it will exert a pressure longitudinally in the manner of a toggle joint to close its attached switch point, and simultaneously the other hinged bar is opened, and draws upon the other switch point to open it. And upon a movement of the operating rod in the reverse direction, a precisely reverse action will take place, the open point will close and the closed point will open. Of course if the switch is properly set for an approaching train the corresponding rock arm will be already down and no action will take place. The operating rod extends preferably beyond the switch and a rock shaft S provided with rock arms 31 and 32 serves to prevent a train coming from that direction from running into an improperly set switch. The hinged bars are preferably crossed in the manner of the letter X which insures the corresponding action thereof without altering the positions of the switch points, and the inclined striking surfaces do not take the full severity of the blow from the train since the hinged joints exert a certain spring action to open and close them during a portion of their action similar to that of springs. Hence all springs can be dispensed with.

Having described the invention what I claim as new and desire to secure by Letters Patent is:—

1. The combination with the rails of a main and switch track, and switch points therefor, of a pair of toggle bars hinged respectively for opening in opposite directions, each bar having one extremity secured to a rail and the other extremity secured to a switch point.
2. The combination with the rails of a main and a switch track, oppositely located switch points therefor, a pair of hinged bars adapted to open in opposite directions with each bar having one end pivotally connected with one of said switch points, and having the other end pivotally connected with one of said rails, an operating device therefor upon the track and an actuating device for the track operating device, said actuating device being located upon a train member.
3. The combination with main and switch tracks and switch points therefor of hinged bars transversely arranged across the track, said bars hinged to open laterally in opposite directions, a rod pivotally connected with the hinges of said bars, and extending along the track to the point of operation, a rock shaft, and rock arms thereon, one of said arms pivotally attached to said rod, operating train devices for moving said rock arms, and intermediate striking surfaces operatively connected with said rock arms, substantially as described.

In testimony whereof I hereunto set my hand this 19th day of February 1908.

WM. L. KUBACH.

In presence of—

WM. M. MONROE,
J. SHARP MAXWELL.
